UNITED STATES PATENT OFFICE.

EDWARD PATRICK LEACH, OF HAILEYBURY, ONTARIO, CANADA.

CONCRETE-MIXER.

1,324,257.

Specification of Letters Patent.

Patented Dec. 9, 1919.

Application filed July 21, 1919. Serial No. 312,424.

To all whom it may concern:

Be it known that I, EDWARD P. LEACH, of the town of Haileybury, in the District of Temiskamin, Province of Ontario, Canada, have invented certain new and useful Improvements in Concrete-Mixers, of which the following is a specification.

This invention has for its object the provision of a simple and cheap, easily operated hand mixer, which will mix the concrete as thoroughly as a power machine.

I attain my object by means of the constructions hereinafter described and illustrated in the accompanying drawings in which—

Figure 1 is a perspective view, partly broken away, showing my device set up for operation;

Fig. 2 a plan view of the box; and

Fig. 3 an end view of the same showing particularly the door.

In the drawings like numerals of reference indicate corresponding parts in the different figures.

1 is a stand, which may be of any suitable construction, provided with the open bearings 2 in which may rest the trunnions 3 of the box 4. This box is substantially rectangular and of elongated form, its length being several times its breadth and the depth nearly equal to the width.

The box is provided at one end with a door 5 preferably hinged and provided with a pivoted latch 6 adapted to engage the keepers 7.

Perpendicular to the bottom of the box and spaced from the sides thereof is an inclined central baffle 8 formed of wood or sheet metal or wood sheathed with metal. At each end of the box is located an inclined baffle 9 perpendicular to the bottom inclined from the side at a point adjacent one end of the central baffle to a point toward the middle of the end of the box. These baffles may be made of wood or sheet metal, or wood sheathed with metal.

An opening 10 is preferably formed in the top of the box intermediate the center and one end through which any ingredients of the concrete or the water may be introduced if desired, though normally such introduction of the solids would be through the door 5. A similar opening may be formed at the other side of the center for convenience in

observing the action of the mixer and the condition of the batch.

Handles 11 are preferably secured to each end of the box for convenience in tilting the same.

The operation of the device is as follows. To fill the mixer, it is tilted to bring the door uppermost. The sand, cement and crushed stone or gravel are then introduced through the door and the latter closed. The box is then tilted on its trunnions to bring each end uppermost twice, thus thoroughly mixing the dry ingredients, which slide from end to end first at one side of the central baffle and then at the other. Water is then introduced through the openings in the top of the box and the box is again tilted back and forth until the contents are sufficiently mixed. The box is emptied by opening the door 5 and allowing the contents to slide out.

What I claim as my invention is:—

1. A concrete mixer comprising a substantially rectangular elongated box provided at each side with a trunnion, a door closed opening at one end, a narrow central substantially parallel sided baffle spaced from the sides of the box, inclined relative thereto and perpendicular to the bottom, and a baffle toward each end of the box perpendicular to the bottom and inclined from the side at a point adjacent one end of the central baffle to a point toward the middle of the end of the box.

2. A concrete mixer comprising a substantially rectangular elongated box provided at each side with a trunnion, a narrow central substantially parallel sided baffle spaced from the sides of the box, inclined relative thereto and perpendicular to the bottom, and a baffle toward each end of the box perpendicular to the bottom and inclined from the side at a point adjacent one end of the central baffle to a point toward the middle of the end of the box, the top of the box being partly open intermediate the center and one end.

Signed at Haileybury this 10th day of July, 1919.

EDWARD PATRICK LEACH.
